UNITED STATES PATENT OFFICE.

RICHARD C. HILLER AND DAVID W. WADE, OF CLEVELAND, OHIO.

STARTING DEVICE FOR GAS-ENGINES.

1,037,622.

Specification of Letters Patent.

Patented Sept. 3, 1912.

Application filed December 21, 1910. Serial No. 598,571.

To all whom it may concern:

Be it known that we, RICHARD C. HILLER and DAVID W. WADE, citizens of the United States, residing at Cleveland, in the county 5 of Cuyahoga and State of Ohio, have invented certain new and useful Improvements in Starting Devices for Gas-Engines, of which the following is a specification.

This invention relates to starting devices 10 for gas engines, and is particularly adapted and intended for use on an automobile, to provide a device by which the engine can be started from the seat or usual position of the driver.

15 The invention includes means which will prevent any possible injury from back fire or kick of the engine.

In the accompanying drawings—Figure 1 is an elevation in partial side elevation showing the manner of applying the device to 20 an automobile. Fig. 2 is a plan view, partly in section, of the apparatus.

Referring specifically to the drawings, 6 indicates a casing which is mounted upon 25 the frame of the vehicle, and this casing has side bars 7 and 8 containing cam like projections or inclines 7^a and 8^a respectively, the function of which is described herein- 30 after. Mounted in supports on the casing is the fixed shaft 9, with a sleeve 10 loose thereon, said sleeve being integral with a gear 10^a, and having ratchet teeth 10^b at one end.

11 is a coöperating ratchet member loose 35 on the shaft 9, and provided with a lever arm 11^a connected by a rod 12 to a suitable operating lever as illustrated at 12^a, located in convenient position for operation by the driver, when the invention is applied to 40 automobile use. A spring 13 bears against the member 11 and tends to throw it into engagement with the ratchet teeth 10^b of the sleeve 10. The member 11 has thereon a cam projection 15 which works against the 45 incline 8^a, and when the member is turned to throw the cam against said incline the member 11 is forced out of engagement with the member 10, the spring 13 being then compressed. When the member 11 is swung 50 back, the spring returns the same to re-engagement with the member 10.

16 is a shaft which is supported partly in bearings in the casing referred to and partly on the frame of the machine, and this shaft 55 is capable of limited movement axially. It carries a pinion 19 fast thereon and in mesh

with the gear 10^a, and a spring 17 in compression between the pinion and the side piece of the casing normally holds said shaft in the position illustrated in Fig. 2. 60 The other end of the shaft has a bevel pinion 18 thereon adapted to mesh with bevel pinion 24 on the engine shaft 23, which latter may be the ordinary crank shaft of the engine. Mounted to turn on 65 the shaft 16 is a cam member 22, with a lever arm 20 connected by rod 21 to an operating lever 21^a. The cam 22 abuts at one side against a shoulder 22^a on the shaft 16, and at the other side with its cam surface 70 against the incline 7^a on the side piece 7.

The operation is as follows:—When it is desired to start the engine the rod 21 is pulled, and by means of the cam 22 acting against the incline 7^a the shaft 16 is shifted 75 axially until the pinion 18 meshes with the pinion 24. The lever 12^a is then worked back and forth, thereby rocking the member 11, and on the backward movement its teeth engage the teeth 10^b and turn the gear 80 10^a, which motion is communicated through the pinion 19, shaft 16 and pinions 18 and 24, to the engine shaft. When the lever 12^a is swung forwardly the cam 15 strikes the incline 8^a and rides up the same, thereby 85 disengaging the ratchet teeth. The operation may be repeated, if necessary to start the engine. When the engine starts the lever 21^a is released and the spring 17 shifts the shaft 16 and disengages the pinions 18 90 and 24, the cam 22 sliding down the incline 7^a.

Having thus described our invention, what we claim as new and desire to secure 95 by Letters Patent is:—

1. In a starting device for gas engines, the combination with the engine shaft, of a longitudinally shiftable shaft, gears between said shafts, a spring pressing the shiftable shaft to position with the gears 100 disengaged, manually operated means to shift the shaft against the pressure of the spring to engage the gears, and manually operated means to turn the shiftable shaft, including a clutch and devices for automatically disengaging the clutch during reverse movement.

2. In a starting device for gas engines, the combination with the engine shaft, of a connected clutch member and gear wheel, 110 a manually operated member engageable with said clutch member to turn the same

and the gear in one direction, means operating on said manually operated member to disengage the same and open the clutch on reverse movement, and transmission mechanism between said gear and the engine shaft, including a longitudinally shiftable shaft, a spring tending to shift said shaft and disengage the transmission mechanism when the shaft is turned in one direction, 10 and a cam acting on the shaft to shift the

same and engage the transmission mechanism when the shaft is turned in the opposite direction.

In testimony whereof, we do affix our signatures in presence of two witnesses.

RICHARD C. HILLER.
DAVID W. WADE.
